UNITED STATES PATENT OFFICE.

FREDERIC E. BALDWIN, OF NEW YORK, N. Y.

ACETYLENE-LAMP.

1,174,037.

Specification of Letters Patent.

Patented Mar. 7, 1916.

Application filed March 18, 1914. Serial No. 825,456.

To all whom it may concern:

Be it known that I, FREDERIC E. BALDWIN, a citizen of the United States, residing at New York, county and State of New York, 5 have invented certain new and useful Improvements in Acetylene-Lamps, of which the following is a full, clear, and exact description.

The object of my invention is to produce 10 an acetylene miner's lamp having an igniting device which can be easily removed for adjustment and repair and can also be securely and firmly locked in proper position when required for use.

15 The following is a description of an embodiment of my invention, reference being had to the accompanying drawings, in which,

Figure 1 shows a front elevation of a 20 lamp embodying my invention, with the burner tip omitted. Fig. 2 shows a side elevation of the same lamp partly in section. Fig. 3 shows a front elevation of the reflector. Fig. 4 shows a detail of the 25 reflector. Fig. 5 shows details of the igniting device. Fig. 6 shows other details of the igniting device. Figs. 7 and 8 show details of the bearing and wheel.

Referring more particularly to the drawings, A is a lamp-body having an outlet and burner tube 1 projecting laterally from the side thereof and a reflector-support 3 forming part of the lamp-body. A reflector 4 carries an internally screw-threaded bushing 4' which screws onto the burner tube 1 so that the reflector is carried thereby. Surrounding the burner tube 1 and inside the reflector-support 3 is a movable socket 5 attached to which is a screw-threaded pin 35 or base 6 on which is screwed the outer portion of the igniting device. The igniting device consists of the socket 5, the pin or base 6, a bearing 7 having internal screw-threads engaging the screw-threads upon the base 6, a friction wheel 8, a piece of sparking material 9, preferably what is commercially known as "Auermetall", and the spring 10 which forces the sparking material against the wheel, the sparking material and spring being inside the bearing. The bearing 7 passes through the reflector at the hole 11 and is flattened on the side 7a which contacts with the reflector-support 3 so as to be held thereby from turning. 50 The hole 11 in the reflector is such that its upper edge presses upon the bearing of the

igniter so as to maintain the flat side of the bearing against the edge of the reflector-support, thus locking the bearing in position and preventing it from turning. The 60 support 3 has some resiliency in the inwardly extending portion 12 between its base and the outer ring 13, and the reflector 4 being of thin metal is also resilient. The resiliency of one or both of these parts permits the reflector after it has been screwed on the burner tube sufficiently to engage the burner support to be further turned until the igniter wheel 8 is brought below the burner tube which is the most desirable position for it. 70

In assembling the parts, the pin or base 6 is projected through the hole 11 in the reflector and the bearing 7 carrying the friction wheel 8, sparking material 9 and internal spring 10 is screwed thereon until the sparking material is forced by the pin 6 into sufficiently intimate contact with the friction wheel 8. The socket 5 is then placed over the collar or bushing 4' carried by 80 the reflector and the reflector is screwed upon the burner tube 1, care being taken that the flat side 7a of the bearing, which is parallel to the axis of the friction wheel 8, is brought into engagement with the outer 85 rim of the reflector-support 3. The reflector is then turned until it firmly engages the reflector-support and the ignition device is brought below the burner tube, the resiliency heretofore referred to permitting this 90 exact adjustment. The burner tip 14 is then placed upon the burner tube 1.

The igniting device being carried by the burner tube and the reflector-support, which form parts of the lamp-body, is firmly held 95 in position without being carried by the reflector which serves simply to maintain it against turning, so that when it is placed in such a position that the burner tube lies in the plane of the friction wheel, it will be 100 locked in that position. In my preferred form, the bearing of the igniting device is made triangular in cross-section, since drawn brass wire of that shape and of the proper size can be obtained so as to make it 105 unnecessary to machine the bearing for the purpose of obtaining the flat locking side thereon. Except for this advantage in doing away with a certain amount of machining, the shape of the bearing is unimportant 110 so long as it has a flat side properly related to the plane of the friction wheel.

The friction wheel is provided with teeth in the ordinary manner which should attack the sparking material when the wheel is rotated in a counter-clockwise direction shown by the arrow in Fig. 2.

- 5 When constructed as above described, the base of the igniter being anchored by the burner-tube and the bearing thereof resting against the reflector support and maintained in engagement therewith by the reflector, the device can stand rough usage without bending, breaking or giving away and is easily removable for adjustment and substitution or repair. The socket 5 is preferably not clamped tightly between the reflector and the lamp-body and so does not interfere with the angular adjustment of the ignition device, which is permitted by the flexibility of the reflector and support.
- 10 20 As will be evident to those skilled in the art, my invention permits of various modifications without departing from the spirit thereof or the scope of the appended claims.

What I claim is:

- 25 1. In an acetylene gas generating lamp, a water tank section having a gas outlet on one side thereof, a reflector through which said gas outlet discharges in combination with a frictionally operated igniter, one end of which is connected to a base located behind said reflector and carried by said water tank section, and the other end of which projects through said reflector into proximity to the discharge from said outlet, said other end being maintained in position by said reflector.
- 30 2. In an acetylene lamp, a lamp-body having a gas outlet in one side thereof, and a reflector-support, in combination with a reflector held against said support, and a frictionally operated igniting device, one end of which is connected to a base located behind said reflector and the other end of which rests upon said reflector-support and projects through said reflector into proximity with said discharge from said outlet.
- 35 3. In an acetylene lamp, a lamp body having a burner tube projecting laterally from the side thereof, a reflector-support surrounding said tube, a reflector through which said tube projects and engaging said reflector-support, a frictionally operated igniting device projecting through said reflector, the inner end of the igniting device surrounding said burner tube and the outer portion resting on and supported by the reflector-support so that its outer end is in suitable proximity to the discharge from said outlet.
- 40 4. In an acetylene lamp, a lamp body having a burner tube projecting laterally from the side thereof, a reflector-support surrounding said tube, a reflector through which said tube projects and engaging said reflector-support, a frictionally operated igniting device projecting through said reflector so as to bring the outer end of the igniting device in proximity to the discharge of said burner tube, the inner end being movably carried by said burner tube.
- 45 5. In an acetylene lamp, a lamp body having a burner tube projecting laterally from the side thereof, a reflector-support surrounding said tube, a reflector through which said tube projects and engaging said reflector-support, a frictionally operated igniting device projecting through said reflector, the inner end of the igniting device surrounding said burner tube and the outer portion resting on and supported by the reflector-support so that its outer end is in suitable proximity to the discharge from said outlet, said reflector maintaining said outer portion in position, said outer portion having a flattened surface where it engages the reflector-support.

niting device projecting through said reflector, the inner end of the igniting device surrounding said burner tube and the outer portion resting on and supported by the reflector-support so that its outer end is in 70 suitable proximity to the discharge from said outlet, said reflector maintaining said outer portion in position.

5. In an acetylene lamp, a lamp body having a burner tube projecting laterally from 75 the side thereof, a reflector-support surrounding said tube, a reflector through which said tube projects and engaging said reflector-support, a frictionally operated igniting device projecting through said reflector, the inner end of the igniting device surrounding said burner tube and the outer portion resting on and supported by the reflector-support so that its outer end is in 80 suitable proximity to the discharge from 85 said outlet, said reflector maintaining said outer portion in position, said outer portion having a flattened surface where it engages the reflector-support.

6. In an acetylene lamp, a lamp body having a burner tube projecting laterally from the side thereof, a reflector-support surrounding said tube, a reflector through which said tube projects and engaging said reflector-support, a frictionally operated igniting device projecting through said reflector, the inner end of the igniting device surrounding said burner tube and the outer portion resting on and supported by the reflector-support so that its outer end is in 90 suitable proximity to the discharge from said outlet, said reflector maintaining said outer portion in position, said outer portion being triangular in cross section and having a screw-threaded connection with the inner 95 end of said device.

7. In an acetylene lamp, a lamp body having a laterally projecting screw-threaded burner tube, and a resilient reflector-support surrounding said tube, in combination with a reflector engaging said support and having screw-threads engaging the threads upon the burner tube, a frictionally operated igniting device projecting through said reflector so as to bring the outer end of the 115 igniting device in proximity to the discharge of said burner tube, the inner end being movably carried by said burner tube.

8. In an acetylene lamp, a lamp body having a laterally projecting screw-threaded burner tube, and a reflector-support surrounding said tube, in combination with a resilient reflector engaging said support and having screw-threads engaging the threads upon the burner tube, a frictionally operated igniting device projecting through said reflector so as to bring the outer end of the igniting device in proximity to the discharge of said burner tube, the inner end being movably carried by said burner tube. 120

65 125 130

9. In an acetylene lamp, a lamp body having a laterally projecting screw-threaded burner tube, and a reflector-support surrounding said tube, in combination with a resilient reflector engaging said support and having screw-threads engaging the threads upon the burner tube, a frictionally operated igniting device projecting through said reflector so as to bring the outer end of the igniting device in proximity to the discharge of said burner tube, the inner end
- 10

being movably carried by said burner tube, said outer portion being rotatably adjustable relative to said inner end and provided with a flattened surface engaging said reflector-support and maintained in such engagement by said reflector. 15
